REGULATOR AND BURNER APPARATUS

Alfred F. Schumann, Baltimore, Md., and Alexander J. Turpin, Stewart Manor, N. Y., assignors to Hanck Manufacturing Company, Brooklyn, N. Y., a corporation of New York

Application July 8, 1939, Serial No. 283,512

3 Claims. (Cl. 299—140)

The invention relates to mixer and burner apparatus suitable for the intimate mixture and combustion of various fluids, particularly as fuels in a gaseous, liquid, or even powdered solid state, for example, as in the mixing, or atomizing, of a combustible oil or gas or powdered fuel with air or steam or with a further combustible gas.

The invention has for an object the provision of apparatus of this nature whereby, within the range of action of the same, a predetermined ratio may be maintained between two fluids supplied thereto, for example, in the case of burner apparatus to afford and maintain under variable output the desired atmosphere in a combustion chamber, thereby avoiding any danger of a change, say from an oxidizing to a reducing condition, or from an efficient to an inefficient flame.

20 A further object of the invention is to provide a burner apparatus admitting of the manual or mechanical regulation of the mixer apparatus in a manner whereby the selected ratio between the fluids is not changed throughout the range 25 of variation of the total supply or output; also to permit of a change in the initial supply of the one fluid to alter the characteristic of the discharge.

In carrying out the invention, for example as 30 embodied in burner apparatus, there is combined with a suitable burner member having an adjustable discharge opening and means for varying the effective area thereof in a manner to afford a predetermined flow characteristic of the discharge of one fluid therethrough, a valve for supplying fuel to the discharge means, said valve being of a nature to afford a similar flow characteristic.

Provision is made, also, for manually establishing the desired port area ratio between the 40 valve and the burner discharge openings, and to insure the maintenance of a constant pressure upon the fluids to be mixed, as in securing ample capacity in the medium supplying mains 45 to substantially the point of use. Regulating means for two separate fluids are so controlled that a predetermined ratio between the fluids is constantly maintained throughout the range of operation of the apparatus; and the combination permits, also, of initially setting the flow of one of the fluids to afford the desired volume thereof.

The nature of the invention, however, will best be understood when described in connection 55 with the accompanying drawings, in which:

Fig. 1 is a plan view of the novel apparatus; and Fig. 2 is an elevation thereof.

Fig. 3 is a longitudinal section through the apparatus with connecting head omitted; and 60 Fig. 4 is a transverse section thereof, taken on

the line 4—4, Fig. 3 of the drawings, and looking in the direction of the arrows.

Referring to the drawings, the burner member is shown to consist of a suitable elongated casing or body having a longitudinally disposed chamber 10 into which the atomizing gaseous medium, as air under requisite pressure, is to be supplied. The casing is provided with a removable tip 11 having the delivery outlet 12 located axially with respect to the casing.

10 Fitting coaxially within the body is the fuel supply nozzle 13 which extends from the rear of the casing to the outlet end thereof, terminating in a head 14 provided with circularly disposed radial outlets 15, the nozzle being bored 15 axially to afford communication to these outlets and designed to terminate at the opposite end in a head 16 or the like provided in its outer surface with a varying area valve port 17 in communication with the bore of said nozzle. 20

Intermediate the casing and nozzle member and axially adjustable therein is a tubular member 20 having peripheral openings 21 to admit air from the interior of the casing to the interior of said tubular member and about the nozzle outlets 15, the tube extending beyond said outlets and being provided with an outlet 22 for mixed fuel and air. The said tube outlet 22 flares toward the delivery outlet 12 of the casing and terminates in juxtaposition thereto. 30 The inner surface of this tube provides a constricted annular portion or throat 23 affording a secondary orifice about the neck of the nozzle, the surface immediately in advance of and succeeding said constricted portion flaring in opposite directions. The design of the orifice, together with a further air orifice hereinafter described, is such that a predetermined flow characteristic, for example a straight-line flow characteristic, will be attained in the delivery of the 40 gaseous medium.

The periphery of the said tube, furthermore, is separated from the casing and forms with the delivery end thereof a tapering annular or primary orifice 24 contracting toward the outlet 12, which orifice may be varied in cross-sectional area in accordance with axial adjustment of the said tube, which, to this end, has a sliding fit at the rear portion of the casing and about the corresponding end of the nozzle member, or rather an intermediate sleeve element 25. Provision is made for axially displacing the tube 26 as through the angular movement about the longitudinal axis of the casing of rockable means such as an arm 26 extending radially from a connecting member or bracket 27 whose one arm 27' is radially connected with the said sleeve. 50 55

This bracket with rocking member is adapted to be secured, also, through a further radially disposed arm 27'' of length equal to that of the 60

arm 27, to a spindle 28 to which it may be adjustably locked by means of a nut 29, with interposed spring-washer 30, threaded over the end of the spindle, or rather an attached flanged head 31. Spindle 28 passes through a stuffing-box 32 and through a cover 33 secured to the head 16, which cover is recessed to afford a valve chamber 34. In this chamber is mounted on the spindle for rotation therewith a valve piece or disk 35 designed to move over the port 17 in the head 16, the effective area of opening of the port being determined by the position of said valve piece relatively thereto, which valve piece is shaped to afford therewith a predetermined flow characteristic conforming to that of the other fluid. The amount of fuel fed through the valve will thus be determined by the position of the operating handle or rocking member 26, fuel being introduced to the chamber 34 through a suitable connection 36 extending externally of the head 16. The position of the said valve piece 35 relative to port 17 may be initially adjusted to the desired location by loosening the nut 29 and manually turning the head 31, which adjustment may be indicated on the scale 37 provided on cover 33. A further scale 38 cooperates with the arm 26 to indicate volume being discharged by the apparatus.

With the angular movement imparted to the valve piece through turning of the spindle 28 by the member 26, which may be accomplished either manually or mechanically, provision is made to also correspondingly reciprocate the tube 20 in a manner to vary the area of the primary orifice 24 in the same sense. For example, the sleeve 25 which is mounted intermediate the tube 20 and the casing 10 at the rear end of said tube, has provided therein a peripheral longitudinal slot 40 extending inwardly from its inner edge and designed to receive a pin 41 secured to said tube. This pin extends also into a helical slot 42 of the casing so that if the said sleeve be turned, the tube will be accordingly reciprocated axially of the nozzle member 13 and outlet 12, and will be displaced with respect to the said outlet to vary the area of opening of orifice 24.

Angular motion is communicated to the sleeve 25 by connecting the same through radial arm 27 to the bracket 27 which effects movement also of the valve spindle 28, so that both the valve and the tube will be simultaneously actuated for regulating the volumes of the two fluids supplied by the burner apparatus; and the proportion of the one to the other, as initially set, will be substantially maintained throughout the range of the burner as the operating member 26 is accordingly moved.

We claim:

1. Apparatus of the nature set forth, comprising a cylindrical casing having at one end a tubular conical discharge tip with axial outlet for fluid, said casing having connection with a source of fluid medium, a movable tube mounted coaxially in the casing, its one end affording with the outlet thereof an annular discharge area, means rockably mounted on the casing to oscillate about its longitudinal axis, together with mechanism including an element disposed radially of the longitudinal axis of the casing intermediate the rockable means and the movable tube to displace the latter longitudinally for adjusting the effective discharge area; a valve mounted at the opposite end of the casing, means for varying the effective port area of the valve, said valve communicating

with the interior of said tube and with a further source of fluid supply; means including an element disposed radially of the longitudinal axis of the casing to transmit movement to the port varying means of the valve from said rockably mounted means to regulate the effective port area of the valve simultaneously with the regulation of said annular discharge area and in the same sense, and adjusting means cooperating with said second radially disposed element and the valve to change selectively the relative effective area of said port with respect to said annular discharge area.

2. Apparatus of the nature set forth, comprising a cylindrical casing having at one end a tubular conical discharge tip with axial outlet for fluid, said casing having connection with a source of fluid medium, a movable tube mounted coaxially in the casing, its one end affording with the outlet thereof an annular discharge area, means rockably mounted on the casing to oscillate about its longitudinal axis, a sleeve fitting over the end of the tube opposite its outlet end and between said tube and the casing, the sleeve having a longitudinal slot from its inner edge, a pin secured to the tube, passing through the slot of the sleeve and fitting a helical slot of the casing; a valve mounted at the opposite end of the casing; means for varying the effective port area of the valve, said valve communicating with the interior of said tube and with a further source of fluid supply; means including respective elements disposed radially of the longitudinal axis of the casing and connecting the valve with said sleeve to regulate the effective port area thereof simultaneously with the regulation of said annular discharge area and in the same sense, means cooperating with one of the radially disposed elements to adjust the effective port area of the valve and including a flanged spindle for rotating the latter, and a nut threaded over the outer end of the spindle, together with an intermediate spring washer adapted to bear upon the end of one radially disposed element rotatably fitted to the spindle between its flange and the said nut.

3. Apparatus of the nature set forth, comprising a cylindrical casing having at one end a tubular conical discharge tip with axial outlet for fluid, said casing having connection with a source of fluid medium, a movable tube mounted coaxially in the casing, its one end affording with the outlet thereof an annular discharge area, a sleeve fitting over the end of the tube opposite its outlet end and between said tube and the casing, the sleeve having a longitudinal slot from its inner edge, a pin secured to the tube, passing through the slot of the sleeve and fitting a helical slot of the casing; a valve mounted at the opposite end of the casing, communicating with the interior of said tube and with a further source of fluid supply and provided with means for varying its effective port area; a valve-operating spindle in the longitudinal axis of the casing; and bracket means including two arms of equal length disposed radially of the longitudinal axis of the casing and respectively connected with the said spindle and with the said sleeve, and an operating arm for rocking said bracket to regulate thereby simultaneously the said port area and the said annular discharge area and in the same sense.

ALFRED F. SCHUMANN.
